US00D642989S

(12) **United States Design Patent**
Montena et al.

(10) **Patent No.:** **US D642,989 S**
(b4) **Date of Patent:** ** Aug. 9, 2011

(54) **WEATHER PROOFING SYSTEM FOR COAXIAL CABLE CONNECTORS**

(75) Inventors: **Noah Montena**, Syracuse, NY (US);
Chris Natoli, Fulton, NY (US)

(73) Assignee: **John Mezzalingua Associates, Inc.**,
East Syracuse, NY (US)

(**) Term: **14 Years**

(21) Appl. No.: **29/381,622**

(22) Filed: **Dec. 21, 2010**

Related U.S. Application Data

(63) Continuation of application No. 29/376,600, filed on Oct. 8, 2010, now Pat. No. Des. 631,848, which is a continuation of application No. 12/760,134, filed on Apr. 14, 2010.

(57) **CLAIM**

The ornamental design for a weather proofing system for coaxial cable connectors, as shown and described.

DESCRIPTION

FIG. 1 is a front perspective view of the present invention showing our design for a weather proofing system for coaxial cable connectors;

FIG. 2 is a back perspective view thereof;

FIG. 3 is a top view thereof, the claimed portion of which is a mirror image to the bottom view thereof

FIG. 4 is a right side view thereof, the claimed portion of which is a mirror image to the left side view thereof;

FIG. 5 is a front view thereof; and,

FIG. 6 is a back view thereof.

The dash-dot line in the figure drawings is included for the purpose of illustrating environment and forms no part of the claimed design.

1 Claim, 4 Drawing Sheets
